UNITED STATES PATENT OFFICE

171,939

BUTTER CONTAINER OR THE LIKE

Charles N. Hubsch, Seattle, Wash.

Application October 25, 1952, Serial No. 21,985

Term of patent 14 years

(Cl. D44—5)

To all whom it may concern:

Be it known that Charles N. Hubsch, a citizen of the United States, residing at Seattle, Washington, has invented a new, original, and ornamental Design for a Butter Container or the like, of which the following is a specification, reference being had to the accompanying drawings, forming a part thereof, in which:

Figure 1 is a perspective view of a butter container, showing my new design;

Figure 2 is another perspective view thereof on a reduced scale;

Figure 3 is a top plan view thereof;

Figure 4 is a rear elevational view thereof;

Figure 5 is an end elevational view thereof; and

Figure 6 is an enlarged fragmentary sectional view taken on 6—6 of Figure 4.

I claim:

The ornamental design for a butter container or the like, as shown.
